PUMPING UNIT

Stanley H. Hobson, Rockford, Ill., assignor to
 Geo. D. Roper Corporation, Rockford, Ill., a
 corporation of Illinois

Application April 2, 1932, Serial No. 602,670

4 Claims. (Cl. 103—218)

This invention relates to a pumping unit for various purposes, but in this instance especially designed for use in connection with a hydraulic lift, such as are used in automobile service stations and other places.

The principal object of my invention is to provide an extremely compact unit of the kind referred to in which all of the working parts are enclosed for protection as well as neatness in 10 appearance, but are nevertheless quickly and easily accessible for inspection and repair, if the occasion arises. In accordance with this object, I provide a storage tank disposed vertically in elevated position and resting on a jacket disposed therebeneath, whereby to provide a housing under the tank for the rest of the unit. Enclosed in this housing is a pump directly connected with the bottom of the tank, and a motor directly connected with the pump for driving 15 the same, the pump and motor being suspended together from the bottom of the tank with the motor disposed vertically above the pump for compactness.

Other objects and advantages of the invention 20 will soon appear in the course of the following specification, in which reference is made to the accompanying drawings, wherein—

Figure 1 is a central vertical section through a pumping unit made in accordance with my invention;

Fig. 2 is a horizontal section on the line 2—2 of Figure 1;

Fig. 3 is a more or less diagrammatic view of a typical lift installation, and

Fig. 4 is a sectional detail on the line 4—4 of Figure 1, showing the relief valve.

The same reference numerals are applied to corresponding parts throughout the views.

Referring for a moment to Fig. 3, the numeral 40 5 designates a conventional lift having parallel troughs 6 on the platform 7 onto which an automobile may be run to be elevated by means of a plunger 8 working in a cylinder 9. Most lifts for this purpose have a pump down in the lower 45 end of the plunger to transfer oil from the plunger to the cylinder to elevate the platform. Some of these lifts have the pump driven by a motor mounted in the upper end of the plunger, and one type has the motor mounted in an oil-tight housing in the bottom of the plunger so as to 50 permit direct connection with the pump and avoid the disadvantages of having to use a drive shaft extending the full length of the plunger. However, there are serious objections to those 55 constructions, because the entire lift has to be

taken apart to get at the pump or motor. These objections are all avoided in accordance with my invention by providing a unit such as that designated generally by the numeral 10 which can be placed at some distance from the lift and has only 60 an oil line 11 extending therefrom to the top of the cylinder 9, whereby to deliver oil under pressure to the cylinder to raise the plunger. The unit 10, briefly stated, comprises a storage tank 12, a pump 13 for pumping oil from the tank 65 through the line 11 to the cylinder 9, and an electric motor 14 for driving the pump. Thus, all of the working parts are completely divorced from the lift and located where they are easily accessible for inspection and repair. Units of 70 this kind can, of course, be used in changing over air lifts to hydraulic operation, using the piping already installed to conduct the oil from the pumping unit to the lift cylinder.

Referring now more particularly to Figs. 1 75 and 2, it will be seen that the tank 12 is disposed vertically in elevated relation to the ground or floor on which the unit is to rest, and has a jacket 15 disposed therebeneath to support the same and also provide a housing under 80 the tank for enclosure of the pump and motor, for protection of these working parts, especially if the unit is placed outdoors, and also to make for compactness and neatness in appearance. The pump 13 is substantially of the same construction as those provided for installation in the lower end of the lift plungers, but in this instance is fastened by its flange 16, which otherwise abuts the lower end of the plunger, to the lower end of a casing 17, which is connected by 85 means of a pipe 18 with the bottom of the tank 12. The pump 13 has a screened intake or suction port 19 communicating with the suction chamber 20 on one side of the intermeshing pumping gears 21 and 22 appearing in dotted outline in Fig. 2. A discharge chamber 23 is provided on the other side of the pumping gears, as indicated in Fig. 2, and a spring-seated check valve 24 opens to permit discharge of oil under pressure from said chamber into a casing 25 90 fastened below the pump to the casing 17, as shown. The oil line 11 mentioned before is connected with the casing 25, to conduct the oil to the cylinder 9. Naturally, the valve 24 opens only when the pump is operated and closes the 95 moment the pump stops, whereby to support the lift platform in any elevated position. The oil can be returned by by-passing it from the casing 25 to the casing 17 through a manually operated release valve 26. This valve is normally held 100 105 110

seated by a compression spring 27, but is arranged to be forced open by means of a push rod 28 to allow oil to flow from the casing 25 into a passage 29 cored in the pump casing. The oil finds its way from the passage 29 into the casing 17 through a small hole 30, whereby to restrict the flow enough to insure a sufficiently slow descent of the lift platform. The push rod 28 is operated by means of a tappet 31 mounted on a rod 32 received in a bearing 33 on top of the casing 17. The rod extends laterally from the casing through a hole in the jacket 15 and has the outer end bent at right angles to provide a handle 34 for operating the same. It is no doubt clear from the foregoing description that oil or whatever fluid is used is stored in a sufficient quantity in the tank 12 to take care of a predetermined rise of the plunger 8 in the cylinder 9, and when the pump 13 is driven by the motor 14, the oil is delivered to the pump by gravity through the pipe 18 and discharged under pressure through the line 11 extending to the cylinder. The lift platform is accordingly raised and will be supported in any position by reason of the valve 24 closing and trapping the oil in the line 11. Then when the lift platform is to be lowered, it is only necessary to open the valve 26 by means of the handle 34 to allow the oil to return to the storage tank.

I prefer to provide a pressure relief valve 50 for establishing emergency communication between the discharge chamber 23 of the pump 13 and the casing 17, or, in other words, between the discharge chamber 23 and the suction chamber 20 of the pump. This emergency communication is to be had only when the pressure in the chamber 23 exceeds a predetermined limit beyond which there would be danger of the motor 14 burning out. Such a thing would be caused by abnormal loading of the lift. The relief valve, as clearly appears in Fig. 4, comprises a body 51 threaded into the top of the casing of the pump 13 for communication with the discharge chamber 23 on the one hand, and communication with the casing 17 or suction chamber 20 on the other hand. The body 51 is hollow and has ports 52 in the side walls thereof which are normally sealed by a plunger 53 held in abutment with the bushing 54 by the compression spring 55. The spring 55 has a predetermined loading, and its pressure may be increased by adjustment of the bushing 54, as is thought to be self-evident. When the pressure in the discharge chamber 23 exceeds a predetermined limit, the plunger 53 is moved against the action of the spring 55 to allow oil to escape from the discharge chamber through the ports 52 into the casing 17 and thence to the suction chamber 20. In other words, when an overload occurs, the motor continues to operate the pump but the oil is not delivered to the line 11 but simply allowed to by-pass from the discharge chamber back to the suction chamber. Obviously, the relief valve 50 will be provided according to what is considered a safe loading of the lift, having due regard to the horse power rating of the motor and the pressure rating of the pump.

The pump 13 together with the casings 17 and 25 is supported from the tank partly by the pipe connection 18 and partly by bars 35 fastened at their upper ends as at 36 to brackets 37 welded or otherwise suitably secured to the bottom of the tank. The bars 35 have their lower ends fastened as at 38 to an upwardly extending portion 39 of the casing 17. The last mentioned

portion terminates in a ring 40 in which a counterbore 41 is provided to receive a pilot portion 42 provided on the bell housing of the motor 14, disposed endwise vertically over the pump, between the pump and the bottom of the tank, and having its armature shaft coupled as at 43 with the driven shaft 44 of the pump 13. In other words, the pump and motor are suspended below the tank. I have found that this makes for most quiet operation, because the vibration incident to the driving of the pump by the motor cannot be transmitted directly to the floor and is absorbed to a large extent in the suspension means. The motor and pump are made easily accessible for inspection and repair by providing a door 45 in the jacket 15. The motor is preferably removable through the door opening. The supports 46 on the inside of the jacket 15 on which the lower end of the tank 12 rests are such that the tank can be lifted off the jacket to afford access to the pump whenever it may be found necessary to remove the same for inspection, repair, or replacement.

It is believed the foregoing description conveys a good understanding of all of the objects and advantages of my invention. While reference has been made throughout the description to use of this invention in connection with hydraulic lifts, it should be understood that the invention is not limited to that or any other specific application. For example, while the tank 12 in this case is an atmospheric gravity tank, being open to the atmosphere by means of the vent 47 in the top thereof, it should be evident that units could be made in which the tank would be a pressure storage tank, in which the line 11 would be a suction line and the pipe 18 a discharge connection, instead of the other way around, as has been herein described. The structure disclosed in my Patent #1,764,307 of a water system pumping unit is an illustration of another type of unit to which the present invention is applicable, and, of course, still other units will suggest themselves to those skilled in the art. The appended claims have, therefore, been drawn so as to cover all legitimate modifications and adaptations.

I claim:

1. In a pump unit comprising a storage tank disposed vertically in elevated relation to a support, and means extending from the support up to the tank to support the same so as to leave the space clear under the tank, a suction casing closed at the top and open at the bottom adapted to receive the suction side of a pump therein, a pipe connected to the top of said casing and extending upwardly therefrom to the bottom of the tank for the double purpose of affording communication between the tank and casing for delivery of water to the latter by gravity and for the purpose of partially supporting said casing from the tank bottom in elevated relation to the support, an open top discharge casing having a pipe extending therefrom for conducting fluid under pressure to a device to be operated thereby, a pump interposed between and forming a partition separating the suction casing from the discharge casing, said pump being rigidly secured in place between said casings with the suction side thereof drawing fluid from the suction casing and the discharge side discharging fluid under pressure into the discharge casing, the suction casing having an upwardly extending portion, and the pump having the driven shaft thereof extending through the top wall of the discharge casing into said upwardly extending portion, an

- electric motor demountably supported on end on said upwardly extending portion, means providing a detachable driving connection between the armature shaft of said motor and the driven shaft of the pump, and one or more suspension members secured to the tank bottom at the upper end and to the upwardly extending portion at the lower end, whereby to cooperate with the first mentioned pipe to suspend the parts named from the tank bottom. 5 the top wall of the suction casing, and manually operable means for communicating movement to said rod to open the valve against the action of the spring means, said last mentioned means comprising a rod rotatably received in a horizontal bearing on the pump casing and extending laterally therefrom and having a handle on the outer end thereof for turning the same, and a tappet mounted on said rod for oscillation therewith and engaging the upper end of the valve actuating rod. 80
2. A pump unit as set forth in claim 1 including a valve in the discharge casing seating upwardly to close an opening for establishing communication between the discharge casing and the suction casing through the pump, spring means normally holding the valve seated, an actuating rod extending from the valve upwardly through the top wall of the suction casing, and manually operable means for communicating movement to said rod to open the valve against the action of the spring means. 15 85
3. A pump unit as set forth in claim 1 including a valve in the discharge casing seating upwardly to close an opening for establishing communication between the discharge casing and the suction casing through the pump, spring means normally holding the valve seated, an actuating rod extending from the valve upwardly through the top wall of the suction casing, and manually operable means for communicating movement to said rod to open the valve against the action of the spring means, together with a restriction plug having an orifice of a predetermined size through which the fluid must pass in flowing from the discharge casing into the suction casing, for the purpose described. 20 90 95
4. A pump unit as set forth in claim 1 including a valve in the discharge casing seating upwardly to close an opening for establishing communication between the discharge casing and the suction casing through the pump, spring means normally holding the valve seated, an actuating rod extending from the valve upwardly through the top wall of the suction casing, and manually operable means for communicating movement to said rod to open the valve against the action of the spring means, together with a restriction plug having an orifice of a predetermined size through which the fluid must pass in flowing from the discharge casing into the suction casing, for the purpose described. 25 100
